(57) **CLAIM**

The ornamental design for a surgical sponge, as shown and described.

DESCRIPTION

FIG. 1 is an upper perspective view of a surgical sponge of our new design.

FIG. 2 is a top plan view of the surgical sponge of FIG. 1.

FIG. 3 is a bottom plan view of the surgical sponge of FIG. 1.

FIG. 4 is a front-end view of the surgical sponge of FIG. 1.

FIG. 5 is a rear-end view of the surgical sponge of FIG. 1.

FIG. 6 is a right-side view of the surgical sponge of FIG. 1; and,

FIG. 7 is a left-side view of the surgical sponge of FIG. 1. The broken lines are included for the purpose of illustrating breakaway lines, and form no part of the claimed design.

The surgical sponge is shown with a symbolic break in its length. The appearance of any portion of the article between the break lines forms no part of the claimed design.
